[57] **CLAIM**

The ornamental design for a flexible dust cover for a monitor, as shown and described.

DESCRIPTION

FIG. 1 is a top rear perspective view of a flexible dust cover for a monitor showing my new design;

FIG. 2 is a bottom front perspective view thereof;

FIG. 3 is a right side elevational view of the flexible dust cover of FIG. 1; the left side elevational view being a mirror image thereof; and,

FIG. 4 is a view taken along line 4—4 of FIG. 3.
The broken lines are shown in the views of illustrative purposes only and form no part of the claimed design.
